UNITED STATES PATENT OFFICE.

JAMES A. NOLAN, OF BOWERSTON, OHIO, ASSIGNOR TO THE MINING SAFETY DEVICE COMPANY, OF BOWERSTON, OHIO, A CORPORATION OF OHIO.

SAFETY DEVICE FOR MINES.

1,337,943.

Specification of Letters Patent. Patented Apr. 20, 1920.

Application filed May 2, 1918. Serial No. 222,096.

To all whom it may concern:

Be it known that I, JAMES A. NOLAN, a citizen of the United States, residing at Bowers-
ton, in the county of Harrison and State of
Ohio, have invented new and useful Im-
provements in Safety Devices for Mines, of
which the following is a specification.

This invention relates to improvements to
that form of safety apparatus illustrated in
my United States Patent 1,307,732, dated
April 22, 1919, and has for its primary ob-
ject to provide mechanism whereby the
wheels of a car may be effectively gripped
so that the car will be held against dis-
placement during the dumping operation.

An object of the invention is to provide
mechanism whereby the flanged plate in my
patented device can be dispensed with, and
the wheels of the car gripped in a manner
to prevent any vibration thereof.

With these and other objects in view the
invention will be better understood from
the following detailed description taken in
connection with the accompanying drawing
25 wherein;

Figure 1 is a plan view of the mechanism
showing the elevator dotted for the sake of
clearness.

Fig. 2 is a side elevation of a pair of
wheels showing the same engaging the stops.

Briefly stated the invention consists of ar-
ranging a predetermined number of stops
shaped to engage a predetermined portion
of the wheels so the car will be held during
35 the dumping operation, and connecting
mechanism thereto, whereby the stops will
be thrown into engagement with the wheels
of the car at the proper time when a car
passes onto the elevator, and be released
40 from the wheels when the car is to move
from the elevator.

One construction of mechanism to ac-
complish this result is illustrated in the
drawing consisting of a front pair of stops
45 1 and a rear pair of stops 2 pivoted to the
elevator as illustrated at 3 so as to swing
to positions over the rails or to one side of
the rails. Each stop is provided with an
arcuate depression 4 the wall of which is
50 adapted to engage a predetermined amount
of the peripheral surface of a car wheel
when the stop is thrown to an operative po-
sition as clearly shown in Fig. 2. By this
arrangement it will be seen that when the

stops are in an operative position the car 55
will be prevented from leaving the rails on
the elevator due to the stops engaging a pre-
determined amount of the peripheral sur-
face of the wheels.

My invention also consists of mechanism 60
of a construction to give the shoes the proper
movement to properly engage the wheels.
In this particular showing of my invention
I provide two sets of mechanism, one for the
front pair of stops and the other for the 65
rear pair of stops of a somewhat similar
construction. The mechanism for the front
stops is identical to that protected in my
patent heretofore mentioned, and consists
of a shaft 5 mounted in bearings 6 for rota- 70
table as well as longitudinal movement.
One end of the shaft has connected thereto
a crank arm 7 arranged to strike a projec-
tion 8 when the elevator reaches a pre-
determined level, so that the stops 1 may be 75
thrown into an inoperative position. The
shaft 5 is connected to the stops by links 9
while a spring 10 is arranged to normally
hold the stops in an operative position to en-
gage the car wheels. To complete the mech- 80
anism I provide a pivoted trigger 11 adapt-
ed to be moved by a passing car wheel and
connected to the rod 5 by a chain 12. The
trigger is provided for the purpose of giving
longitudinal movement to the shaft 5 to dis- 85
engage the crank arm 7 from the projection
8, when a car passes onto the elevator, so
that the stops 1 may be free to move to an
operative position.

The mechanism for the rear stops 2 in-
cludes a shaft 13 which is mounted for ro-
tatable movement, but not longitudinal
movement. This shaft is connected to the
stops by links 14 operating as set forth in
my patent heretofore mentioned. The crank 90
arm 15 of the shaft 13 terminates in a weight
16 so that when the arm is free of the pro-
jection 17 the weight will move the stops
into an operative position to engage the
rear wheels of the car. 100

From the foregoing description taken in
connection with the accompanying drawing
it should be apparent that I provide an ap-
paratus of substantial construction and
capable of locking the car to the elevator in 105
such a manner that extra elements coöper-
ating with the stops will be dispensed with.

When an empty car has been passed from

the elevator the parts are in a position as illustrated in Fig. 1 with a result that when a loaded car enters upon the elevator the front wheels strike the trigger 11 and retract the shaft 5 with the result that the arm 7 is disengaged from the projection 8, and the spring 10 rotates the shaft 5 which through the medium of the links 9 forces the stops over the rails in an operative position 10 to engage the wheels of the incoming car. Upon the initial upward movement of the elevator the gravitational action of the weight 16 will rotate the shaft 13 in the proper direction to cause the links 14 to 15 throw the shoes 2 to an operative position in engagement with the wheels of the car. Thus it will be seen that the shoes are now 20 in a position to effectively engage the wheels as shown in Fig. 2 of the drawing so that the car will be prevented from leaving the rails during the dumping operation. As will be understood, member 8 is mounted, in practice, in any suitable manner so as to be raised by arm 7 to permit raising of the cage without tripping shaft 5.

It is to be understood that the structural embodiment of the invention as a whole and its various features as shown is merely illustrative and not restrictive, since I am well 30 aware that many of the details of construction can be widely varied without departing from the spirit of the invention. I therefore do not desire to be limited in these particulars or in any others, except as set forth 35 in the appended claims.

Having described my invention, what I claim is:

1. In combination, a cage, front and back 40 pairs of stops carried thereby, independent shafts rockably mounted on said cage, operating connections between said shafts and the respective pairs of stops, means for normally holding said shafts in rocked adjustment so as to hold the stops in operative position, means for rocking the shafts so as to move the stops into inoperative position upon the cage reaching the limit of its downward travel, and means actuated by a car entering the cage for releasing the operating shaft 45 for the front stops so as to permit return of the same to operative position, the shaft for the rear stops being released upon raising of

the cage so as to permit return of the rear stops to operative position.

2. In combination, a cage, front and back 55 pairs of stops carried thereby, an operating shaft rockably mounted on the cage and operatively connected to the back pair of stops, means for normally holding said shaft in rocked adjustment so as to hold the back 60 stops in operative position, means coöperating with said holding means for rocking the shaft in such direction as to move the back stops into inoperative position as the cage approaches the limit of its downward movement, a second shaft mounted on the cage for both axial and rocking movement, operating connections between said second shaft and the front stops, means for normally holding the second shaft in rocked adjustment so as to hold the front stops in operative position, an arm carried by the second shaft, a member positioned to be struck by 70 said arm as the cage approaches the limit of its downward movement so as to rock the shaft in such direction as to move the front stops into inoperative position, means for normally holding said second shaft extended, and means actuated by a car entering the 75 cage for retracting the second shaft so as to move the arm thereof out of contact with said member and permit return of said front stops to operative position.

3. In combination, a cage, front and back 80 pairs of stops carried thereby, a back shaft 85 rockably mounted on the cage, operating connections between said shaft and the back stops, a weighted arm extending from said shaft and serving to normally hold said shaft in rocked adjustment to hold the stops in operative position, a front shaft mounted on the cage for rocking and axial movement, operating connections between said front shaft and the front stops, means for normally holding the front shaft in rocked adjustment so as to hold the front stops in operative position, a trip arm extending from 90 said front shaft, means for normally holding the front shaft extended, and means actuated by a car entering the cage for re- 100 tracting said front shaft.

In testimony whereof I affix my signature.

JAMES A. NOLAN.
